UNITED STATES PATENT OFFICE.

CHARLES JOSEPH STEELE, OF JERSEY CITY, NEW JERSEY.

DEVICE FOR SPACING THE UPPER AND LOWER LAPS OF ENDLESS CLOTHES-LINES.

1,091,089.

Specification of Letters Patent. Patented Mar. 24, 1914.

Application filed September 22, 1913. Serial No. 791,182.

To all whom it may concern:

Be it known that I, CHARLES J. STEELE, a citizen of the United States, residing at Jersey City, in the county of Hudson, State 5 of New Jersey, have invented certain new and useful Improvements in Devices for Spacing the Upper and Lower Laps of Endless Clothes-Lines; and I do hereby declare the following to be a full, clear, and 10 exact description of the invention, such as will enable others skilled in the art to which it appertains to make and use the same.

This invention relates to clothes lines and has for an object to provide means for holding 15 the upper lap and lower lap of an endless loop clothes line spaced apart and at the same time preventing the lower lap from which the garments are suspended from being blown up and entangled with the upper 20 lap when the clothes are actuated by breezes.

With the above objects in view the invention consists of certain novel details of construction and combination of parts herein-after fully described and claimed, it being 25 understood that various modifications may be made in the minor details of construction within the scope of the appended claims.

In the accompanying drawing illustrating 30 this invention:—Figure 1 is a front elevation showing the application of my invention to a clothes line. Fig. 2 is a longitudinal sectional view on the line 2—2 Fig. 1. Fig. 3 is a front elevation showing a modified form of the invention. Fig. 4 is a 35 longitudinal sectional view on the line 4—4 Fig. 3.

Referring now to the drawing in which like characters of reference designate similar parts, 10 designates an endless loop 40 clothes line which is trained over sheaves 11 and 12 attached respectively to a window casing 13 and outdoors post 14, these parts being of the usual and well known type.

In carrying out my invention I provide a 45 sheave 15 which is mounted in an inverted J-shaped rod 16, the sheave engaging down upon the upper lap 17 of the clothes line. I also provide a second sheave 19 which is mounted in a J-shaped rod 20 and is engaged 50 upon the lower side of the lower lap 21 of the clothes line. The shanks of both rods overlap and are provided with respective registering slots 22 and 23 through which an adjusting bolt 24 is passed to adjustably secure the sheaves at any desired 55 distance apart. A weight 25 is attached to

the J-shaped rod of the lower sheaves by means of a rod 26, this weight serving to prevent abnormal swaying of the lower lap of the clothes line when the clothes are applied thereto so that entanglement of the lower lap with the upper lap is positively prevented.

It has been found by experiment that in case of there being very little weight of garments on the lower lap, that the weight 25 has a tendency to pull down the upper lap of the clothes line and permit of the lower lap lifting out of engagement with the lower sheave 19. To obviate this disadvantage, I 60 have provided the attachment shown in Figs. 3 and 4, such attachment being applied directly to the parts above carefully described, and consisting of an inverted V-shaped rod 27 that is provided at the apex 65 with an eye 28 and is provided at the terminals of the legs with rollers 29. The above mentioned adjusting bolt 24 is passed through the eye 28 and the rollers 29 are disposed to ride upon the upper side of the 70 lower lap of the clothes line on opposite sides of and at equal distances from the lower sheave 19 whereby the lower lap of the clothes line is positively prevented from lifting up from engagement with the lower 75 sheave.

From the above description it will be seen that I have provided an extremely simple device which will prevent the upper lap and lower lap of a clothes line from becoming 80 entangled, and which device furthermore will be formed of a few simple parts that may be constructed at a minimum cost and will not easily get out of order.

What is claimed, is:—

1. The combination with an endless loop clothes line of means for separating the upper lap and lower lap of the clothes line including an upper sheave engaging the top side of said upper lap, a lower sheave engaging the bottom side of said lower lap, respective rods carrying said sheaves and having shanks overlapping between said upper lap and said lower lap, means adjustably securing said shanks together, and a weight carried by the rod of said lower sheave.

2. The combination with an endless loop clothes line of means for spacing the upper lap and lower lap of the clothes line apart including an upper sheave engaging the upper side of said upper lap, a lower sheave

engaging the lower side of said lower lap, respective rods carrying said sheaves and having overlapping ends, a bolt passed through said overlapping portions and adjustably securing the same together, an inverted V-shaped rod having an eye at the apex engaged on said bolt, and rollers on the legs of said rod engaging the top side of said lower lap on opposite sides of and at

equal distances from said lower sheave, and a weight carried by one of said rods.

In testimony whereof, I affix my signature, in the presence of two witnesses.

CHARLES JOSEPH STEELE.
